WILLIAM GENTRY SHELTON, OF NEW YORK, N. Y.

SELF-CONTAINED ENGINE HAND-TOOL.

1,201,363.

Specification of Letters Patent. Patented Oct. 17, 1916.

Application filed March 17, 1913. Serial No. 754,918.

To all whom it may concern:

Be it known that I, WILLIAM GENTRY SHELTON, a citizen of the United States, residing in the borough of Manhattan, city, county, and State of New York, have invented certain new and useful Improvements in Self-Contained Engine Hand-Tools, of which the following is a specification.

10 Among the objects of the invention is the provision of a drill stock or hand-piece carrying a self-contained engine, the hand-piece and engine being in the form of and constituting a hand-tool. The invention also 15 comprises controlling means carried by the hand tool for the transmission mechanism between the engine shaft and the driven spindle, and for the motor.

10 The rotary parts of a motor which is carried by a hand tool requiring the most delicate and precise manipulations must be small for lightness and rotated at a high speed for power, too high indeed for direct application to certain tools, for instance a dental drill or allied tool. The ability to 25 effectively reduce the speed and increase the power at the point of utilization was a problem the solving of which made the use of this form of tool feasible.

30 In the drawings accompanying this specification one practicable embodiment of a form of the invention is illustrated, wherein—

35 Figure 1 is a view partly in central, longitudinal or axial section and partly in elevation; Fig. 2 is a section taken on the plane at about the line 2—2 of Fig. 1 looking down. (The section upon which Fig. 1 is taken is illustrated in this view by the line 40 1—1). Fig. 3 is a view partly in elevation and partly in section substantially transverse to the section of Fig. 1. The plane of this section is illustrated at the line 3—3 in Fig. 2. Fig. 4 is a transverse section taken 45 on a plane at about the line 4—4 of Fig. 1 looking up. Fig. 5 is a detail of the switch and contact mechanism. Fig. 6 is a diagram of the wiring.

50 The drill stock or part 7 carrying the driven shaft 13 in the illustration is a commercial form of dental hand-piece and carries a dental engine, the whole comprising a hand tool having a self-contained engine. The hand tool illustrated has the usual 55 coupling screw 8 to which is attached the

casing of the engine. In the present illustration the coupling 8 is connected with a coupling member 9. The coupling member 9 has a flange 10 for engaging the member 11 of the hand-piece for holding this in position relatively to the coupling 8. In this form of hand-piece the chuck 12 of the driven shaft 13 is closed by moving the hand-piece away from the coupling 8 and is opened by moving it toward the same.

60 The main portion 14 of the engine casing is shown having a screw-threaded connection with the coupling 9. This main portion constitutes a frame as well as the housing of the engine. The engine in the present 65 instance is driven by means of an electric motor. The motor which is employed is a single bearing motor which has been found most efficient for steadiness as well as lightness. The field magnets 15 together with 70 their coils 16 are mounted on this member 14. A bearing 17 in the form of a tube or hollow cylinder is secured at one end, the lower end in the illustration, to the housing 14, and the other end extends upwardly 75 through the field magnets and the coils and upon this bearing is mounted the armature 18 which has a spindle or shaft 19 extending through the bearing 17 and also a bearing 20 for engaging the outer surface of 80 the bearing 17. A motor of sufficient lightness for use in a hand tool to get the requisite power will have to run at a too high rate of speed for driving certain tools. It is therefore necessary to gear the speed down 85 between the motor or engine shaft 19 and the driven shaft 13. The transmission connection for effecting this reduction in the present illustration comprises a roller gearing.

90 A member 21 having an external bearing surface is shown mounted upon the engine shaft 19. Outside this is a member 22 having an internal bearing surface, and between these members is a race of balls 23 carried by a ball cage 24. The ball cage 100 carries a series of pins 25, three in the present illustration, and the driven shaft 13 carries a coupling for such pins, in the present instance a disk 26 having a series of notches 27 for receiving and engaging the pins 25. 105 When the member 21 is rotated, and the member 22 is free to rotate, it will rotate in a reverse direction to the direction of rotation of the member 21, and the ball cage 110 remains substantially stationary. Upon

either slowing down or stopping the rotation of the member 22 the ball cage will be rotated in the direction of rotation of the member 21 but at a reduced speed, the reduction being about $2\frac{1}{2}$ to 1 in the present showing. A brake or friction member 28 is provided for this purpose, and is carried by a resilient arm 29 which is mounted upon the hand piece, in such position that 10 the operator may readily engage it by his fingers when he desires to rotate the driven shaft 13 and whatever tool 30 he may be employing in the chuck.

The engine casing not only comprises the 15 members above referred to but a cover member 31 for the main frame member 14. This cover member is oscillatorily mounted upon the bolts 32 which extend from the frame member 14 through the field magnets and 20 through slots 33 in the cover member 31. These slots are for the purpose of limiting the amount of oscillation of the member 31. This member is also provided with a flange 34 surrounding the free end of the frame 25 member 14 for making a secure joint between these parts and guiding the oscillation of the member 31. The purpose of such oscillation is for changing the position of the brushes and switches for effecting a 30 reversal of rotation of the armature.

The circuit is substantially as follows: The lead line 35 comes into the casing with the lead line 36 in the form of a cable, the lead line 35 passes around the field coils 37 35 and 38, and then has two contact buttons 39, 40; the lead line 36 has two contact buttons 41 and 42. A pair of buttons 43 and 44 are associated with the brushes 45 and 46 respectively, which run upon the armature 47. 40 When it is desired to drive the armature in one direction the cap member 31 of the engine casing will be moved to the position to bring the parts as illustrated in Figs. 5 and 6, wherein the contact button 43 is in engagement with the contact button 41 and the contact button 44 will be in engagement with the contact button 40. When, however, it is desired to reverse the direction of the armature and thereby reverse the direction 45 of the tool, the operator may, while still holding the tool in operative position, move the cover member 31 to its other limit of movement and bring the button 43 into engagement with the button 39, and the button 44 into engagement with the button 42, thereby changing the direction of current and the direction of rotation of the armature and also of the tool 30. The buttons connected with the lead lines are shown 50 mounted upon insulation bridges 48, which are held in position upon the bolts 32.

From the foregoing description it will be apparent that drills and other tools may be readily inserted in and removed from the chuck upon the driven shaft, as occasion

may demand, and that the reduction transmission gearing will reduce the speed transmitted to these tools to a safe working speed, and this without undue vibration. It will also be apparent that the tool may be 70 stopped and started without stopping and starting the motor, and that the tool may be started up at slow speed by permitting a frictional engagement between the brake member 28 and the transmission member 22, 75 thus permitting a certain amount of slipping of such member 22, or that the full speed may be had when desired, by bringing the member 22 to a complete rest, and that the motor may be reversed either during the use of the tool and while the transmission connection is in efficient or working position or when these are at rest as occasion may demand.

The reduction transmission in the illustration is connected to the driven shaft and located at one end of the hand piece and the chuck on such shaft is located at the opposite end of the hand piece. This is of particular advantage in a mechanically controlled clutch.

In the illustration the power is shown applied to the inner of the three members of the clutch and taken from the intermediate member, although the power may be applied 95 to any one of the three members and taken from either of the others.

In the construction described the use of the particular form of transmission gearing is of importance for several reasons. In 100 order to bring the tool within the compass of weight which is permissible, an extremely small and rapidly rotating motor must be provided, and in such constructions toothed reduction gearing is unsuitable for the purpose. Furthermore, the gearing herein provided is subject to quick and easy control by the finger of the user, moved in a normal direction. It will be understood, however, that the gearing set forth is capable of other 110 uses than that to which it is shown as applied, and is adapted to be located at other points than that disclosed.

While but one embodiment of the invention has been shown for the purpose of illustrating the same, yet it will be apparent that changes may be made within the scope of the claims without departing from the spirit of the invention.

I claim as my invention:—

1. In a self-contained engine hand-tool, the combination with a casing and a hand-piece, of a driven shaft carried thereby, an electric motor mounted in the casing, coupling means between said driven shaft and motor, an electric switch carried by the casing for controlling the current to the motor, and a controlling member for said coupling means carried by the hand-piece whereby the motor and shaft may be instantaneously 125 130

uncoupled at will for coupling the shaft to the motor and uncoupling the same therefrom.

2. In a self-contained engine hand-tool, 5 the combination with a casing, of a hand piece carried thereby, a driven shaft in the hand piece, a motor in the casing, transmission mechanism between the motor shaft and the driven shaft, and a finger piece fast with 10 the hand piece and extending into the casing for controlling the transmission mechanism.

3. In a self-contained engine hand-tool, 15 the combination with a casing, of a hand piece carried thereby, a driven shaft in said hand piece, a motor in said casing, and a finger piece carried by the hand piece and extending into the casing for controlling the rotation of the driven shaft.

20 4. In a self-contained engine hand-tool, the combination with a casing, of a hand piece carried thereby, a driven shaft in the hand piece, an electric motor in the casing, transmission mechanism between the motor shaft and the driven shaft, and a finger piece fast with the hand piece and extending into the casing for controlling the transmission mechanism, and means for controlling the current to the motor.

25 5. The combination with a hand piece and a driven shaft mounted therein, of a motor, a casing for the motor having one part carried by the hand piece and carrying the motor, and another part oscillatorily mounted 30 on the other part, and means controlled by the oscillation of such part for controlling the direction of rotation of the motor, and

a controlling member carried by the hand piece for coupling the shaft to the motor and uncoupling the same therefrom. 40

6. The combination with a hand piece and a driven shaft mounted therein, of a motor, a casing for the motor having one part carried by the hand piece and carrying the motor, and another part oscillatorily mounted 45 on the other part and carrying the brushes for the motor, the oscillation of such part serving to control the direction of rotation of the motor, and a controlling member carried by the hand piece for coupling the shaft 50 to the motor and uncoupling the same therefrom.

7. The combination with a hand piece, of a driven shaft carried thereby, a chuck on the shaft at one end of the hand piece and 55 a reduction transmission and clutch on the shaft at the other end of the hand piece, and an actuator for the clutch carried by the said hand piece.

8. The combination with a hand piece, of a driven shaft carried thereby, a chuck carried by the shaft at one end of the hand piece and a member of a transmission mechanism connected to the shaft at the other end of the hand piece, and an actuator for 60 the transmission mechanism carried by the hand piece. 65

In witness whereof, I have hereunto signed my name in the presence of two subscribing witnesses.
